UNITED STATES PATENT OFFICE.

CHARLES A. GREENE, OF NEW YORK, N. Y.

SANITARY CASE.

1,374,849.

Specification of Letters Patent. Patented Apr. 12, 1921.

Application filed April 12, 1919. Serial No. 289,535.

To all whom it may concern:

Be it known that I, CHARLES A. GREENE, a citizen of the United States, and a resident of the city of New York, borough of 5 Manhattan, county of New York, and State of New York, have invented a new and Improved Sanitary Case, of which the following is a full, clear, and exact description.

This invention relates to a new and improved sanitary and instrument case and is particularly adapted for use as a chiropodist case, but, it is understood that it may be used for other purposes.

One of the objects of this invention is to provide a case of the above character compactly and conveniently arranged to carry receptacles of various forms and sizes, so constructed that the various parts carried therein are readily accessible, such parts including an instrument case and contents, sterilizing apparatus, and suitable bandage and cotton receptacles.

A further object is to provide in a case of this character a means to accommodate receptacles of various forms and sizes, said means being readily adjusted or removed to facilitate the cleaning of said case.

A further object is to provide a means within the case which is adapted to permit the ready replacement and use of instruments of varying shapes and sizes, and of the removable racks therefor. This construction also facilitates the cleaning of the case.

Still another object is to provide a collapsible sterilizer support suitably carried by the case and so constructed that when not in use, it may be folded to occupy a minimum space and be moved inside the main case body.

A further object of this invention is to provide a means in an instrument case which may function as a sanitary bottom therefor, and which may be withdrawn to serve as a table or support for the instruments.

Other objects and advantages will be apparent from the accompanying drawings and the following description of one of the preferred forms of this invention.

Similar characters of reference designate corresponding parts in the several views, wherein:

Figure 1 is a perspective view showing the box in an open position and the sterilizing receptacle in proper position upon

the folding support therefor with the heating means therebelow.

Fig. 2 is an end sectional view of the case in a closed position showing the relative position and arrangement of the various parts carried thereby.

Fig. 3 is a broken sectional view of one corner showing the removable partitions and the supporting brackets therefor.

Fig. 4 is a perspective view of the sliding supporting bracket for the partitions.

In the drawings showing one of the preferred forms of this invention, the main outer case portion may be made of any suitable substantial material, and comprises two end pieces 1, 2, connected by a bottom 3 and a back 4, there being provided a front 5 hinged at its lower edge at 6 to the front edge 7 of the bottom. A cover 8 having downwardly extending side portions 1', 2', 4' and 5', adapted to fit over the top edges of the corresponding portions of the main case body, is hinged at 9 to the top edge of the back 4 and is provided at the front with a catch 10 to engage a lock 11, carried by the hinged front 5. A handle 12 is suitably secured to the top of the cover.

Removably carried inside of the case is a suitable sanitary lining composed of a suitable aseptic material, such for example as porcelain, glass or any suitable metals or any other material which may be removed and cleansed. The said lining comprises the removable bottom 13, the ends 14 and 15 and the back 16, the upper edge of said end members 14 and 15 being positioned by guides 15'.

As a means of carrying instruments there is carried on the inner side of the hinged front 5 an instrument case comprising upwardly projecting frame members 17 and 18 spaced and secured by a connecting member 17', and other connecting portions 19 spaced from the bottom member 17' a sufficient distance to slidably receive a removable sanitary bottom 24, which also may be made of any suitable material as above stated, said bottom being so arranged so that when withdrawn, in the direction indicated by the arrow and the dotted lines, from its closed position, it may be used as a table for the instruments. A suitable cover 22 for the instrument case, having downwardly extending side portions 22', is carried by a hinged connection 23 at the top edge of one of the upwardly extending side

edges of the instrument case.

portions 17 of the lower portion of the instrument case.

As a means of permitting the ready removal or replacement of instruments and to facilitate the cleaning of the instrument case, there are provided removable racks 20 having openings therein to properly accommodate suitable instruments, said racks 20 being slidably carried in spaced guides 21 carried by the upwardly extending side portions 17, 18.

As a means of permitting the use of receptacles of varying sizes and in order to facilitate the cleaning of the case, there are provided removable partitions 25 extending longitudinally of the lower portion of the case, slidably carried in suitable brackets, one preferred form herein shown having a grooved portion 27 formed by projecting side portions 27', projecting from an end portion 26, which slidably receives the partition members 25, said bracket being provided at its lower edge with an extending base portion 28 adapted to fit under the bottom lining 13, to be adjustably moved along the edge thereof carrying the ends of the partitioning member therewith to accommodate receptacles of varying sizes. A receptacle is shown dotted in Fig. 1 indicating the position of the receptacle when used.

In the upper portion of the case there is provided as a means of carrying bandages or other material, a rectangular-shaped receptacle or tray 29 having a suitable bottom 35 and connecting side portions, said receptacle extending substantially throughout the entire length and breadth of the upper part of the case and having a cover 30 having downwardly projecting side portions, said cover 40 being hinged to the top edge of one of the sides at 30'. The main tray portion 29 is hinged at 31 to the top edge of one of the side members 4 of the case. As a means of moving the tray to a substantially upright position in order that access may be had to the inner part of the case, an arm 49 is pivotally carried on the bottom of the tray at 49' so that when the tray is raised, the arm will assume the position indicated in Fig. 1 and hold the tray in a raised position, and to lower the tray the arm is moved to the position indicated by the dotted line.

As a means of carrying cotton, there is also provided another receptacle 32 suitably supported beneath the bottom of the tray 29 carried in a substantially central position with reference to the main case portion and at one end thereof, this position serving to conserve the space within the case 60 and permit the positioning of the instrument case carried by the hinged cover within the main case. The cotton receptacle is provided with a hinged cover 33 and a relatively small opening 33' through which the

cotton may be taken. This requires but little exposure of the cotton and hence keeps it in a clean and sanitary condition. Binding posts 29' and 29' are carried insulated from the tray so that if desired, a suitable medical coil may be connected thereto. A 70 suitable catch 34 carried at one of the lower corners of the tray member is provided, and has a projecting end portion adapted to engage a suitable opening 35, in one of the projecting side portions 17 of the cover 22 of 75 the instrument case, so as to hold the front of the case in a closed position, so that if for any reason the lock and catch 10 and 11 should be disengaged by holding the handle 12, the hook 34 engaging the opening 35 80 would hold the front in a closed position and thus prevent the material within the box from falling therefrom.

A simple and compact collapsible sterilizing support is hinged at 36 near one end of 85 the hinged front cover, said support comprising a base 37 and standards 38 and 39 hinged at each end 36 and 40 of said base 37 in such manner that when the sterilizer is not in use, and when it is desired to close 90 the front of the case, the standards 38 and 39 are folded, in the direction indicated by the arrows, upon the base 37, and said base is then moved to a vertical position normal to the cover, it then being in a position to 95 be moved within the main case when the front is moved to a closed position, it being understood that before this is done the cover 22 of the case will be closed and the slidably bottom 24 will be moved within the instrument case. As before stated, when the hinged front is moved to a closed position, the hook member 34 will engage the opening 35 in the side portions 17. The upper end of the folding standards 38 and 39 has 100 a contracted portion 39' adapted to engage a positioning slot formed by the band 42 carried at each end of a fluid receptacle or sterilizer 41. The said receptacle or sterilizer is thus seen to be removably carried at 105 the upper end of the standards 38 and 39, which are shown as being of a substantially rectangular form of a length equal to approximately that of the base 37 of the collapsible support. A removable top 44, having 110 downwardly projecting side portions, is provided for the sterilizer, said top being provided with an opening 46 having a sliding cover 47 therefor, said opening being used to insert the instruments therethrough 115 into the sterilizing liquid. Other openings 48 are provided in which are carried other suitable receptacles 48', which may be used to hold chemicals.

As a means of heating the liquid within 120 the sterilizer 41, there is provided a fuel chamber 43 carried between the standards 38 and 39 on the base 37 of the collapsible

sterilizer support, the length, width and breadth thereof being slightly less than that of the sterilizer 41 so that when not in use, the chamber 43 may be placed within the 5 sterilizer 41 and thus conserve space when the sterilizer is placed within the main case and thus placed adjacent the partition members, as shown in Fig. 2.

As a means of heating the fluid within 10 the sterilizer 41, there is provided a wick or burner 50 at the top of the fuel chamber 43. As a means of holding the top of the main case in a substantially upright position, there is provided eyelets 51, 52, carried by 15 the top 8 and end portion 1 respectively, there being fastened to one of said eyelets one end of a connector 53, there being provided at the other end a hook 54 adapted to engage the eyelet 51 carried by the cover 20 to properly position the top.

It is thus apparent that by this compact and convenient arrangement of parts within the case, when closed, the space in the case is effectively utilized, and, when the case is 25 open for use the parts are so positioned and moved as to be readily accessible.

It is to be noted that the bandage tray and cotton receptacle, the sterilizer, the collapsible support therefor and adjustable 30 brackets are preferably made of sheet metal, but any suitable material may be used therefor.

While but one preferred form of the invention has here been shown, certain changes 35 and modifications thereof may be made

without departing from the spirit and scope of this invention.

Having thus described my invention, what I claim as new and desire to secure by Letters Patent is as follows:

1. A sanitary case comprising a box-like structure and including a front hinged at one edge thereof, an instrument case carried by one side of said front, removable instrument racks therefor, a sterilizer and 45 a collapsible sterilizer support therefor hinged at one side of said front, said support including a base member and upwardly projecting standards hinged at each end thereof.

2. A chiropodist case comprising a box-like structure including a front hinged at one of its edges, removable instrument racks carried thereby and a collapsible sterilizer support hinged at one side of said 55 front, said support including a base and upwardly extending standards hinged at each end of said base adapted to removably support a sterilizing chamber at the upper ends thereof.

3. In a chiropodist case having a front portion pivoted at its lower edge, a sterilizer, a collapsible support therefor, said support being pivoted on said front and comprising hinged members adapted to be 65 folded and moved with the front portion to a position in the chiropodist case when the front is closed.

CHARLES A. GREENE.
